UNITED STATES PATENT OFFICE.

HUGH K. BROWNING, OF RICHMOND, VIRGINIA.

CEMENT-BRICK MACHINE.

1,294,042.

Specification of Letters Patent. Patented Feb. 11, 1919.

Application filed November 16, 1917. Serial No. 202,400.

To all whom it may concern:

Be it known that I, HUGH K. BROWNING, a citizen of the United States, residing at Richmond, in the county of Henrico and 5 State of Virginia, have invented certain new and useful Improvements in Cement-Brick Machines; and I do hereby declare the following to be a full, clear, and exact description of the invention, such as will enable 10 others skilled in the art to which it appertains to make and use the same.

This invention relates to improvements in brick machines of the type forming the subject matter of the Letters Patent granted 15 May 5th, 1914 and numbered 1,095,596, and has for one of its objects the provision of a novel means of mounting the tampers so that they will not become out of alinement with the mold and thereby obviating the danger 20 of injuring the divisional plates constituting a portion of the mold.

Another object of this invention is the provision of novel means of mounting the divisional plates of the molds so that they 25 will be held firmly and be prevented from raising with the tampers and which can be released and swung or partially raised for cleaning the same when desired.

A further object of this invention is the 30 provision of means for sliding the division plates rearwardly to expose the bricks after being molded and which means will, when in its initial position effectively lock the divisional plates in an operative position.

A still further object of this invention is the provision of a brick machine of the 35 above stated character, which shall be simple, durable and efficient, and which may be manufactured and sold at a comparatively 40 low cost.

With these and other objects in view as will become more apparent as the description proceeds, the invention consists in certain novel features of construction, combination 45 and arrangement of parts, as will be hereinafter more fully described and claimed.

For a complete understanding of my invention, reference is to be had to the following description and accompanying drawings, 50 in which:

Figure 1 is a side elevation of a brick machine constructed in accordance with my invention,

Fig. 2 is a vertical sectional view of the 55 same,

Fig. 3 is a perspective view of the bed

plate illustrating the divisional plates partly raised.

Fig. 4 is a fragmentary sectional view illustrating the means of mounting the end 60 divisional plates,

Fig. 5 is a transverse sectional view illustrating the manner of connecting the divisional plates and the mounting of the hopper 65 in relation thereto,

Fig. 6 is a longitudinal sectional view illustrating the divisional plates in an operative position,

Fig. 7 is a front elevation partly in section of the front wall of the mold in an open 70 position,

Fig. 8 is a front elevation of the front wall,

Fig. 9 is a transverse sectional view taken on the line 9—9 of Fig. 8,

Fig. 10 is a fragmentary perspective view of the brake,

Fig. 11 is a perspective view of a modified form of pallet.

Referring in detail to the drawings, the 80 numeral 1 indicates a supporting structure which has formed thereon a plurality of legs 2 mounted upon a suitable foundation 3. The legs 2 are reinforced by braces 4. The supporting structure 1 has formed upon its 85 sides adjacent its forward end bearings 5 which have secured thereto vertical uprights 6. The vertical uprights have their upper ends connected to bearings 7 which are connected by a bar 8 carrying a suitable 90 catch 9. The catch 9 is adapted to engage a tamper supporting bar 10 which has formed thereon a plurality of tampers 11 arranged in spaced relation to each other as clearly illustrated in Fig. 2. The tamper supporting 95 bar 10 has formed upon each end bearings 12 which receive rods 13 and are secured thereto by fasteners 14. The rods 13 are of rectangular formation and are slidably received by the bearings 5 and 7. A bar 15 100 connects the lower ends of the rods 13 and has journaled thereto rollers 16. The rollers 16 are adapted to be engaged by cams or eccentrics 17 carried by a shaft 18 journaled to a pair of the legs 2, whereby upon rotation of the shaft 18 the eccentrics or cams 17 will reciprocate the tampers 11.

A bed plate 19 of skeleton formation is located upon the supporting structure 1 and has its forward end reduced to receive a pallet 20, constituting a bottom wall having end upstanding walls 21 which are spaced from

the ends of the bottom wall for the purpose of forming flanges 22 that project beyond the edges of the bed plate 19 so that the pallet 20 may be readily gripped and lifted from the bed plate when desired. The shoulder formed by the reduced portion of the bed plate 19 has secured thereto a vertical rear plate 23 provided with a plurality of vertical slots to receive a series of divisional plates 24. The divisional plates 24 have extending through their rear ends adjacent their lower edges a shaft 25 on which are positioned spacing collars or rollers 26 that prevent lateral movement of the divisional plates 24 upon the shaft. A shaft 27 extends through the rear ends of the series of divisional plates except the end divisional plates which are indicated by the character A and has positioned thereon a plurality of spacing collars which coöperate with the spacing collars 26 and preventing lateral movement of the divisional plates. The end divisional plates A are of a greater height and length than the remaining divisional plates and are slidably received within grooves 28 formed in ribs 29 carried by the rear longitudinal edges of the bed plate, as clearly illustrated in Fig. 3. It will be noted that the divisional plates that have the shafts 25 and 27 passing therethrough may be swung upwardly into an inclined position as illustrated in Fig. 3 when desiring to clean the same, as the shaft 25 acts as a hinge for the same.

End walls 30 are secured to the ribs 29 and abut the rear wall 23 and are each provided with an elongated slot 31 to receive the ends of the shaft 25 which are provided with rollers 32 which engage the walls of the slots 31 so that the divisional plates may be slid rearwardly between the side walls 30 when desired. The upper edges of the side walls 30 are rabbeted as illustrated at 33 to form supporting shoulders for a hopper 34. The horizontal shoulders formed by rabbeting the upper edges of the side walls 30 are disposed in horizontal alignment with the upper edges of the end divisional plates A as illustrated in Fig. 4 so that the hopper 34 may be slid upon the upper edges of the divisional plates A when desired. The hopper 34 has a sliding bottom wall 35 so that the contents of the hopper may be emptied therefrom when desired. Suitable handles 36 are secured to the hopper and to the sliding bottom wall 35 for the purpose of actuating the same.

A front wall 37 has secured to its lower edge a bar 39 on which are formed spaced ears 40. The spaced ears 40 are pivoted to spaced ears 41 formed upon the forward edge of the bed plate 19. The bar 39 has formed thereon a plurality of spaced reinforcing members 42 that extend upwardly against the front wall 37 to reinforce the same. The

front wall 37 is provided with a plurality of spaced vertical slots 43 which receive the front ends of the divisional plates 24 when the front wall is in a vertical or closed position. An upper bar 44 is secured to the front wall 37 at its upper edge and has formed thereon a plurality of V-shaped lugs 45 that enter the slots 43 into an engagement with V-shaped notches 46 formed in the front end of the divisional plates which will hold said divisional plates in a horizontal position upon the pallet 20 when the front wall is in a vertical or closed position.

Operating levers 46 are secured to the ends of the front wall 37 and have angularly related extensions 47 formed thereon to which are pivoted arms 48. The arms 48 extend rearwardly and are journaled to the ends of the shaft 25 so that upon swinging the operating levers downwardly into a dotted position as illustrated in Fig. 1, the divisional plates are slid rearwardly upon the bed plate 19 to permit the pallet 20 to be removed.

A substantially U-shaped locking member 49 has the ends of its arm portions pivoted to the side walls 30 as illustrated at 50, while its web portion is disposed over the front wall 37. The arm portions are provided with notches 52 adjacent their point of formation to the web portion so as to receive the upper edge of the front wall 37. Ribs 53 are formed upon the side walls 30 and overlie the pivoted ends of the arm portions of the U-shaped locking member 49 so as to limit the downward movement of the same when the front wall has been swung to an open position which prevents the same from interfering with the removal of the pallet 20 from the bed plate.

The shaft 18 has secured to one end thereof a gear 54 which meshes with a gear 55 secured to one end of a drive shaft 56. The drive shaft 56 is journaled to a pair of the supporting legs 2 and has secured thereon a fixed pulley 57 over which a power belt 58 travels. An idle pulley 59 is journaled upon the drive shaft 56 adjacent the fixed pulley 57 for the purpose of receiving the power belt 58 when not desiring to drive or operate the machine.

A belt shifting bar 60 is slidably mounted upon the supporting structure 1 and has formed thereon a pair of spaced fingers 61 that engage upon each edge of the power belt so that upon sliding the bar 60, the power belt may be shifted from one pulley to the other.

A shaft 62 is journaled to pair of the supporting legs and has secured thereto a suitable foot pedal and a rod 63, which rod has its upper end disposed between a pair of spaced lugs 64 formed upon the bar 60, whereby upon actuating the foot pedal, the bar 60 may be slid in one direction against the tension of a spring 65 which will slide

the bar in a reverse direction as soon as the foot pedal is released. The fixed pulley 57 has formed thereon a flange adapted to be engaged by a brake 66 carried by one end of 5 the belt operating bar 60. The brake 66 is provided with a suitable brake lining 67. The brake 66 is adapted to be urged in engagement with the flange of the fixed pulley by the influence of the spring 65 so as to 10 stop the operation of the machine when the power belt has been shifted on the idle pulley.

The pallet 20 is preferably constructed from wood or similar material but may be 15 constructed of metal as illustrated in Fig. 11 which clearly shows a modified form of pallet in which the bottom wall 67 has its edges turned downwardly to form supporting flanges 68. The sides 69 have their lower 20 edges disposed at right angles to form attaching flanges 70 which are bolted to the ends of the bottom wall 67 providing a construction whereby a number of pallets, after being removed from the machine carrying 25 bricks, may be piled one upon the other permitting the supporting flanges 68 to engage the upper edges of the end walls 69 thereby spacing the bricks in each pallet from the bottom wall of the adjacent pallet. To reinforce the upright members 6, suitable 30 braces 71 are secured adjacent their upper ends and to the side walls 30 as clearly illustrated in Fig. 1, thus providing a substantial rigid construction which will prevent 35 lateral movement of the tampers during their operation.

In operation, the operating levers 47 are swung to a vertical position moving the front wall into engagement with the front 40 ends of the divisional plates and are locked in this position by means of a locking member 49. The hopper containing cement or similar ingredients is then slid forwardly upon the end divisional plates A overlying 45 the other divisional plates which are disposed over the pallet 20. The slide bottom 35 of the hopper is then withdrawn so as to permit the contents to fall downwardly between the divisional plates. The hopper 50 is then returned to its normal position resting upon the upper edges of the side walls 30. The tamper bar is then disengaged or 55 released from the catch 9 and simultaneously the operator places his foot upon the foot pedal causing the belt shifting bar 60 to position the power belt upon the fixed pulley 57 which causes the eccentrics or cams to rotate and as they rotate they reciprocate the bars 13 carrying the tampers. The tampers 60 being reciprocated engage the ingredients or cement between the divisional plates compacting the same therein. When the cement has become thoroughly packed between the divisional plates, the operator releases his 65 foot from the foot pedal and the spring 65

causes the bar 60 to shift the power belt on to the idle pulley 59 and simultaneously the brake 66 is applied to the fixed pulley stopping the operation of the machine.

The locking element 49 is then disengaged 70 from the front wall 37 and the operating levers are swung downwardly moving the front wall with the same and simultaneously sliding the divisional plates rearwardly between the side walls 30, leaving the bricks 75 exposed upon the pallet 20. The pallet 20 is then removed from the machine with the bricks thereon and another pallet substituted in lieu thereof. The operating levers are then again swung to a vertical or closed 80 position and locked by the locking element 49 and the machine is again ready for a second operation.

While I have shown and described the preferred embodiment of my invention, it 85 will be understood that minor changes in construction, combination and arrangement of parts may be made without departing from the spirit and scope of the invention as claimed. 90

Having thus described my invention, what I claim is:

1. A brick machine including a mold, bearings located above the mold, bearings located below the mold, rods slidably in 95 said bearings, and a tamper secured to said rods between the first and second-named bearings.

2. A brick machine including a support, bearings carried by said support, vertical 100 uprights secured to and extending above said bearings, bearings secured to the upper ends of the uprights, vertical tamper carrying rods slidably mounted in said bearings and a tamper secured to said rods between 105 the first and second-named bearings.

3. A brick machine including a support, bearings carried by said support, vertical uprights secured to and extending above said bearings, bearings secured to the upper 110 ends of the uprights, tamper carrying rods slidably mounted in said bearings, a tamper secured to said rods between the first and second-named bearings, and a member connecting the second named bearings. 115

4. A brick machine including a support, a vertical frame carried by said support, tamper carrying rods slidably in said frame, a bar connecting the lower ends of said rods, a shaft journaled on said support, and eccentrics secured to said shaft and adapted to engage the bar upon rotation of said shaft to reciprocate said tamper supporting rods. 120

5. A brick machine including tampers, operating means for the tampers, mold box 125 division plates, means hingedly mounting said plates, and means adapted to lock the division plates against swinging movement upon the hinges by and during the upward movements of the tampers. 130

6. A brick machine including tampers, operating mechanism for the tampers, a series of mold division plates, a member extending through said plates, a second member extending through some of said plates to permit such plates to be swung upwardly upon the first member, and means adapted to hold said hinged plates against upward movement by and during the upward movement of the tampers.
- 10 7. A brick machine including tampers, operating mechanism for the tampers, a mold box having a hinged wall, slidably mounted division plates, means carried by said hinged

wall and engaging the division plates to hold them against upward movement by and during the upward movement of the tampers, operating levers secured to said hinged wall, and means connecting the operating levers with the division plates to withdraw said division plates upon swinging said hinged wall into opened position.

In testimony whereof I affix my signature in presence of two witnesses.

HUGH K. BROWNING.
